CLAIM

The ornamental design for a flood light with solar panel, as shown and described.

DESCRIPTION

FIG. 1 is a front, right and top perspective view of a flood light with solar panel, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the flood light with solar panel that form no part of the claimed design.
